CLAIM

The ornamental design for a straight bar concave, as shown and described.

DESCRIPTION

FIG. 1 is a perspective view of a straight bar concave;
FIG. 2 is another perspective view thereof;
FIG. 3 is another perspective view thereof;
FIG. 4 is another perspective view thereof;
FIG. 5 is a front elevation view thereof, the rear elevational view being a mirror image thereof;
FIG. 6 is a top plan view thereof;
FIG. 7 is a bottom plan view thereof;
FIG. 8 is a right-side elevation view thereof; and,
FIG. 9 is a left-side elevation view thereof.

1 Claim, 8 Drawing Sheets
